CIRCUIT INTERRUPTER

Joseph Slepian, Pittsburgh, Pa., assignor to Westinghouse Electric Corporation, East Pittsburgh, Pa., a corporation of Pennsylvania

Application March 27, 1943, Serial No. 480,733

10 Claims. (Cl. 200—148)

1
This invention relates to circuit interrupters in general, and, more particularly, to circuit interrupters of the type which utilize an arc extinguishing gas to effect turbulence within the arcing region to assist in extinguishing the arc drawn during a circuit interrupter opening operation.

An object of my invention is to provide an improved circuit interrupter having cooperable electrodes, in at least one of which are disposed a plurality of gas conducting apertures.

Another object is to provide an improved circuit interrupter which sends a plurality of gas jets at substantially acoustic velocity into the arcing region.

A further object is to provide an improved circuit interrupter which has cooperable perforated electrodes, and to send a plurality of gas jets at near acoustic velocity through the perforations or apertures in one electrode into the arcing region and out the perforations or apertures in the other cooperable electrode also at near acoustic velocity to effect rapid extinction of the arc drawn between the electrodes.

Another object is to provide an improved circuit interrupter having at least one gas conducting passage through one electrode to not only effect turbulence in the arcing region but also to effect a lateral movement of the arc to distribute the heating effect of the terminal of the arc over the surface of the electrode.

A more specific object is to provide an improved circuit interrupter comprising a pair of cooperable electrodes between which an arc may be established, and to provide gas conducting apertures in both electrodes inclined helically in opposite directions to effect both turbulence and lateral arc movement in the arcing region between the electrodes.

Another object is to provide an annular arcing passage between two cooperable electrodes in which the established arc may be moved laterally.

For purposes of illustration I describe my invention as applied to circuit interrupters of the compressed air type. Other gases such as carbon dioxide, hydrogen, etc., may, however, be used.

Further objects and advantages of my invention will readily become apparent upon a reading of the following specification taken in conjunction with the drawings, in which:

Figure 1 is a plan view of a circuit interrupter embodying my invention;

Fig. 2 is a view in cross section taken on the line II—II of Fig. 1;

Fig. 3 is a view in cross section taken on the line III—III of Fig. 2;

2

Fig. 4 is an enlarged fragmentary plan view of the top fixed electrode looking down on the line IV—IV of Fig. 2;

Fig. 5 is an elevational view, partly in section, of a circuit interrupter embodying a modification of my invention;

Fig. 6 is an inverted view in section taken on line VI—VI of Fig. 5; and

Fig. 7 is an inverted view in section taken on the line VII—VII of Fig. 5.

Referring to the drawings, and more particularly to Fig. 2, the reference numeral 1 designates a fixed plate electrode to which a terminal 2 is rigidly attached. The fixed plate electrode 1 has formed therein a plurality of exit apertures 3 inclined helically as more clearly shown in Figs. 3 and 4.

Cooperating with the fixed plate electrode 1 is a second fixed plate electrode 4 which has a contact portion 5, and which has a terminal 6 rigidly connected thereto. The fixed plate electrode 4 has formed therein a plurality of inlet apertures 7 inclined helically as more clearly shown in Fig. 3. It will be observed that the exit apertures 3, provided in the fixed plate electrode 1, are inclined helically in an opposite direction from the direction of the helically inclined inlet apertures 7 formed in the fixed plate electrode 4, as more clearly shown in Fig. 3, the purpose for which 30 will appear more clearly hereinafter.

Disposed between the fixed plate electrodes 1, 4 and maintaining them in spaced relation is an insulating ring 8, more clearly shown in Fig. 2. Also disposed between the plate electrode 1, 4 is 35 an insulating plate 9. Threadedly secured to the fixed plate electrode 4 is an insulating tubular flared conduit member 10, which serves to conduct a suitable arc extinguishing gas, in this instance compressed air, toward the inlet apertures 40 7 disposed in the fixed plate electrode 4, as shown more clearly by the arrows in Fig. 2.

The fixed plate electrode 1 has an upstanding guide portion 11 which serves to guide a movable tubular conducting bridging electrode 12. In the 45 closed circuit position of the interrupter the movable tubular bridging electrode 12 engages the contact portion 5 of the fixed plate electrode 4 to electrically connect the plate electrodes 1, 4. Consequently, the electrical circuit through the 50 interrupter in the closed circuit position (not shown) comprises the terminal 2, the fixed plate electrode 1, the movable tubular bridging electrode 12, contact portion 5 of fixed plate electrode 4 to the other terminal 6 of the interrupter.

55 Exit apertures 3 are also provided in the movable tubular electrode 12 and also in the upstand-

ing guide portion 11, as more clearly shown in Fig. 2. It is, therefore, desirable to prevent a rotation of the movable tubular bridging electrode 12 with respect to the fixed plate electrode 1. The key 13, rigidly secured to the electrode 12 sliding in the longitudinal recess 14 provided in the upstanding guide portion 11, prevents rotation of the bridging electrode 12 with respect to the plate electrode 1.

Referring to Figure 2 it will be observed that the insulating ring 8 cooperates with the insulating plate 9 to form an annular interelectrode arcing passage generally designated by the reference numeral 15 the ends of which are bounded by annular arcing members formed by the inwardly exposed surfaces of electrodes 1 and 4 respectively. The edge portions of the insulating ring 8 and insulating plate 9 adjacent the arcing passage 15 have apertures formed therein to align with the apertures 3, 7 of plate electrodes 1, 4 as more clearly shown in Fig. 2. Positioning pins 18, as more clearly shown in Fig. 2, prevent rotation of the insulating plate 9 with respect to the fixed plate electrode 4.

During the opening operation of the interrupter the movable tubular electrode 12 is moved upwardly by any suitable means to separate from the portion 5 of fixed plate electrode 4 to establish an arc designated by the reference numeral 16 in Fig. 2. The arc extinguishing gas, in this instance compressed air, forced upwardly through the tubular flared conduit 10 passes through the helically inclined inlet apertures 1 of fixed plate electrode 4 to result in a plurality of air jets which enter the annular interelectrode arcing passage 15 turbulently. The air flow through the inlet apertures 1 produces not only a very high turbulence in the annular passage 15, but also produces an angular momentum which causes a mass circulation of the air around the annular interelectrode arcing passage 15 at high velocity. The angular momentum carries the arc 16, which is initially established, rapidly around the annular arcing passage 15 on the extended surfaces of the plate electrodes, 1, 4. Fig. 3 shows the position of the arc 16 after it has been carried part way around the annular arcing passage 15 to a position designated by the reference numeral 17.

I have found that for a circuit interrupter of the type shown in Figs. 1-4 inclusive which is designed for 15,000 volts, 60 cycles, and large currents, that the pressure at the entrance to the inlet apertures 1 in fixed plate 4 may be substantially 60 pounds per square inch absolute pressure. The total area of the inlet apertures 1 is approximately $\frac{1}{8}$ of the effective area of the fixed plate electrode 4. The interelectrode pressure within the annular arcing passage 15 may be 30 pounds per square inch absolute pressure. Consequently the air jets coming into the annular arcing passage 15 through the inlet apertures 1 in fixed plate electrode 4 will have substantially the velocity of sound in air, that is 14,000 inches per second.

The total area of the exit apertures 3 in fixed plate electrode 1 is substantially $\frac{1}{8}$ of the effective area of fixed plate electrode 1. Atmospheric pressure, that is 15 pounds per square inch absolute pressure, prevails outside of the fixed plate electrode 1. Consequently the air jets which pass through the exit apertures 3 in fixed plate electrode 1 will have substantially the velocity of sound in air. The width between the plate electrodes 1, 4 may be approximately $\frac{1}{2}$ inch.

The arc 16 is carried rapidly around the annular arcing passage 15 at high velocity and permitted to play between the annular portions of the electrode plates 1 and 4 relatively unimpeded and unrestricted. At a current zero the arc will not restrike because of the increase in dielectric strength of the air within the annular interelectrode arcing passage 15 caused by the turbulence of the air jets passing through the inlet apertures 1 in plate electrode 4 at substantially acoustic velocity. Also the rotation of the arc 16 around the annular arcing passage 15 distributes the heating effect over the extended surfaces of the electrodes 1, 4 to minimize the emission of ionized metallic particles from the plate electrodes 1, 4. The arc 16 is extinguished at the first current zero, and suitable means not shown may then stop the compressed air flow.

In the embodiment of my invention shown in Figs. 5 through 7 inclusive there is provided a fixed tubular electrode 21 having a plurality of inlet apertures 22 preferably generally uniformly distributed across the face thereof. An insulating gas conduit 23 is threaded secured to the fixed tubular electrode 21, and the passage of gas therethrough is controlled by the electrically actuated valve generally designated by the reference numeral 24.

Surrounding the tubular electrode 21 is an insulating casing 25, in this instance cylindrical, which also serves as a guide for a movable tubular electrode 26. Terminal 27 is rigidly secured to the fixed tubular electrode 21, and a terminal 28 is rigidly secured to the movable tubular electrode 26 as more clearly shown in Fig. 5.

Consequently in the closed circuit position of the interrupter (not shown) the electrical circuit therethrough comprises terminal 28, movable tubular electrode 26, fixed tubular electrode 21, to terminal 27.

Disposed in the movable tubular electrode 26 are a plurality of exit apertures 29 also preferably generally uniformly distributed across the face thereof. The reference numeral 30 generally designates the interelectrode arcing region.

During the opening operation of the interrupter shown in Fig. 5 the movable tubular electrode 26 is moved upwardly to separate from the fixed tubular electrode 21 to draw an arc 31 in the interelectrode arcing region 30 and which is permitted to play relatively unimpeded and unrestricted between the electrodes 21 and 26 now serving as arc terminal members. Simultaneously, a suitable means (not shown) operates the electrically actuated valve 24 to force a stream of gas, in this instance compressed air, upwardly through the insulating conduit 23 and upwardly through the inlet apertures 22 into the arcing region 30.

The compressed air jets passing through the fixed tubular electrode 21 produce turbulence within the interelectrode arcing region 30 to extinguish the arc 31 at the first current zero. The direction of the compressed air flow is indicated by the arrows in Fig. 5.

For a circuit interrupter of the type shown in Fig. 5 designed for 15,000 volts, 60 cycles, and for high current, the separation between the fixed electrode 21 and the movable electrode 26 may be taken as 1 centimeter at arc extinction. The transient peak voltage which the arcing region 30 must stand after current zero will be under 50 kv. This dielectric strength can be insured by providing that the compressed air in this space is at 30 pounds per square inch absolute pres-

sure. After the transient it may fall to normal 15 pounds per square inch absolute pressure.

Compressed air is injected into the arcing region 30 at about acoustic velocity or 14,000 inches per second through the inlet apertures 22 in the fixed electrode 21. The driving pressure is then 60 pounds per square inch absolute. The area of the apertures 22 may be substantially $\frac{1}{6}$ the area of the fixed electrode 21. The area of the exit apertures 29 in movable electrode 26 may be substantially $\frac{1}{6}$ of the electrode area. Therefore, the 30 pounds per square inch interelectrode pressure will discharge the air out through the exit apertures 29 in the movable electrode 26 at substantially acoustic velocity to atmospheric pressure.

The air between the electrodes 21, 26 will be in a highly turbulent state. The intensity factor of the turbulence will be close to acoustic velocity, or 3.10^4 cm./sec. The scale factor of the turbulence will be about 0.5 cm. The effective diffusion coefficient due to this turbulence will be of the order of the product of these factors or about 10^4 .

The time constant for the decay of ionization and temperature in the interelectrode space will be

$$\frac{d^2}{\pi^2 D}$$

where d is the interelectrode separation and D is the effective diffusion coefficient. Taking $d=1$ and $D=10^4$, this gives a time constant of 10 microseconds, which is fast enough to ensure arc extinction in any practical circuit.

Figs. 6 and 7 show a comparison of aperture areas provided in the electrodes 21, 26.

Although I have shown an application of my invention to two different types of circuit interrupters operating at 15,000 volts, 60 cycles, and at high currents it is to be clearly understood that for higher or lower voltage ratings or currents the dimensions and also the pressure of the gas used would necessarily be varied to suit the operating conditions desired.

It will also be apparent that in both embodiments of my invention shown and described, the compressed air is injected in the form of a plurality of air jets at acoustic velocity into the arcing region, and is also exhausted out of the arcing region at acoustic velocity. Using compressed air as the arc extinguishing gas, the velocity of the air jets entering and leaving the arcing region should be in the range from 5,000 inches per second to 14,000 inches per second, the latter figure being the numerical value of acoustic velocity in air. My preferred range of velocities is, however, from 10,000 inches per second to 14,000 inches per second using compressed air.

For other gases the numerical value of the velocity of sound is different from that in air. In hydrogen, for example, the velocity of sound is approximately four times that for air.

Using other gases than air, the range of velocities of the jets entering and leaving the arcing region should be between 30% and 100% of the velocity of sound in the gas used. The preferred range is from 70% to 100% of the velocity of sound in the gas used.

I have found that the ratio of the total inlet aperture area in the inlet electrode to the total exit aperture area in the exit electrode should be in the range from 1:1 to 1:3. My preferred range is between 1:1 $\frac{1}{2}$ to 1:2 $\frac{1}{2}$. In both em-

bodiments shown in the drawings the ratio is 1:2 which gives the best results.

The pressure of the gas on the low pressure side of any of the electrodes 1, 4, 21, 26 should be from $\frac{1}{4}$ to $\frac{3}{4}$ of the gas pressure on the high pressure side of the particular electrode. The preferred pressure is from $\frac{3}{8}$ to $\frac{5}{8}$ of that on the high pressure side of the electrode. In the two breakers shown, the pressure on the low pressure side of any of the electrodes is $\frac{1}{2}$ that on the high pressure side. This I have found to give the best results.

Although I have shown and described specific structures it is to be clearly understood that the same were merely for purposes of illustration, and that changes and modifications may readily be made by those skilled in the art without departing from the spirit and scope of the invention.

20 I claim as my invention:

1. In a circuit interrupter, a pair of relatively movable electrodes between which an arc is established, means forming an annular arcing passage disposed between the electrodes, an annular 25 arcing member disposed at each end of said arcing passage and between which said arc is adapted to be moved relatively unimpeded and unrestricted, said arcing members having a plurality of gas conducting apertures formed therein, and 30 means forcing gas under pressure at high velocity unidirectionally through said apertures and said arcing passage to create a highly turbulent atmosphere therein for extinguishing the arc.

2. In a circuit interrupter, a pair of electrodes 35 between which an arc is established, at least one of the electrodes having a plurality of gas conducting apertures formed therein which are inclined helically.

3. In a circuit interrupter, a pair of cooperable 40 electrodes between which an arc may be established, both electrodes having formed therein a plurality of gas conducting apertures, the apertures in the pair of electrodes being inclined helically in opposite directions.

4. In a circuit interrupter, a pair of cooperable electrodes between which an arc may be established, at least one electrode being substantially flat and having one gas conducting aperture therein which is inclined with respect to the longitudinal axis of the electrode.

5. In a circuit interrupter, a relatively fixed tubular electrode closed at one end except for a plurality of apertures disposed therein, a cooperable movable tubular electrode also closed at 55 one end except for a plurality of apertures disposed therein, a relatively tight fitting insulating casing surrounding the fixed electrode and also serving as a guide for the movable electrode and forming an arcing region between the apertured 60 surfaces of said electrodes, and means for forcing gas through the apertures in the fixed electrode into the arcing region and out through the apertures in the movable electrode at a rate to create within the arcing region a turbulent atmosphere 65 having a high coefficient of diffusion to quickly extinguish the arc drawn between the electrodes.

6. In a circuit interrupter, a pair of electrodes between which an arc is established, means forming an annular arcing passage disposed between 70 the electrodes, at least one of the electrodes having a plurality of gas conducting apertures formed therein which are inclined helically.

7. In a circuit interrupter, a pair of electrodes between which an arc is established, means forming an annular arcing passage disposed between

7
the electrodes, both the electrodes having a plurality of gas conducting apertures formed there-in which are inclined helically in opposite direc-tions.

8. In a circuit interrupter, means of insulating material defining the side walls of an arc chamber, a pair of arc terminal members disposed in spaced relation and arranged with respect to said means of insulating material to enclose the opposed ends of said arc chamber, means for establishing an arc between said arc terminal members, one of said arc terminal members having a plurality of generally uniformly distributed gas inlet passages therethrough, means for moving arc extinguishing gas at high velocity through said inlet passages to create a highly turbulent atmosphere within said chamber, said other arc terminal member having a plurality of generally uniformly distributed gas exhaust passages therethrough the total cross-sectional area of which is such to enable said gas to exhaust from said chamber at a velocity substantially equal to the inlet velocity to enhance the turbulence within the arc chamber and bring about a rapid diffusion of ions and quickly extinguish the arc.

9. In a circuit interrupter, a tubular member of insulating material, a pair of arc terminal members of conducting material adapted to be positioned in spaced relation within said tubular member to provide end walls of an arcing chamber, one of said arc terminal members having a plurality of gas inlet openings therethrough, the other of said arc terminal members having a

5 plurality of gas exhaust openings therethrough, means for establishing an arc between said arc terminal members, and means for causing a high velocity blast of gas to flow longitudinally through said tubular member, said inlet openings in said one arc terminal member causing a high degree of turbulence in said arc chamber, said exhaust openings in said other arc terminal member being so proportioned with respect to said inlet openings to cause said gas to exhaust therethrough at substantially the same velocity as the gas entering said chamber to enhance the turbulent effect in the arc chamber to quickly de-ionize and extinguish the arc and to maintain the gas therein at a predetermined pressure.

10. In a circuit interrupter of the compressed gas type, a pair of spaced generally flat arc terminal members between which an arc is adapted to play, tubular means of insulating material extending between said arc terminal members to define therewith an arc chamber, said arc terminal members having a plurality of apertures therein to permit a unidirectional flow of gas through said arc chamber, means for establishing 20 an arc between said arc terminal members, and means for moving gas under sufficient pressure to produce a flow through said apertures of the order of 30% to 100% acoustic velocity, said apertures being so arranged to produce within said arc 25 chamber a highly turbulent atmosphere having a high effective diffusion coefficient to quickly extinguish the arc.

JOSEPH SLEPIAN.
